UNITED STATES PATENT OFFICE.

CHARLES J. VOLKSTADT, OF NORTH TONAWANDA, NEW YORK.

SNOW-SHOVEL.

1,176,112.

Specification of Letters Patent. Patented Mar. 21, 1916.

Application filed December 18, 1915. Serial No. 67,581.

To all whom it may concern:

Be it known that I, CHARLES J. VOLKSTADT, a citizen of the United States, residing at North Tonawanda, in the county of Niagara and State of New York, have invented new and useful Improvements in Snow-Shovels, of which the following is a specification.

This invention relates to the class of snow shovels having a curved or scoop-like blade of sheet metal stiffened by diagonal or upwardly-converging braces secured to its rear side. Such braces are usually provided at their upper ends with parallel portions or 15 extensions between which the handle is secured.

It has been found in practice that the braces are liable to break at their junction with their parallel extensions, and it is one 20 of the objects of my invention to improve the construction of the shovel with a view of strengthening the braces, so as to withstand the strains to which they are subjected and prevent their breakage at those 25 points.

A further object is to so combine the braces with the handle that the load or strain is exerted principally against the braces, in order to relieve the sheet-metal 30 blade and avoid stripping it from the braces.

In the accompanying drawings: Figure 1 is a perspective view of the shovel with the handle partly broken away. Fig. 2 is a rear 35 view thereof. Fig. 3 is an enlarged horizontal section on line 3—3, Fig. 2. Fig. 4 is an enlarged vertical section on line 4—4, Fig. 2.

Similar characters of reference indicate 40 corresponding parts throughout the several views.

1 indicates the curved sheet-metal blade of the shovel which may be stamped with the customary stiffening ribs or corrugations 2. At its lower edge the blade has the usual tip or horizontal strip 3, fastened to it by rivets 4 or other suitable means.

5 indicates the braces which are applied to the rear side of the blade and which preferably consist of T-irons. They converge 50 upwardly from the lower edge of the blade nearly to its top and are provided at their upper end with substantially parallel upright extensions 6 which terminate at or 55 near the upper edge of the blade. The base flanges of these T-iron braces rest against

the back of the blade to which they are secured by rivets 7 or other suitable fastenings. In the preferred construction shown in the drawings, the webs 8 of the braces 60 terminate near their lower ends and said ends are rigidly secured between the blade and its tip 3 by a pair of the rivets 4. As the webs of the T-iron braces stand at right angles to the plane of the blade, they effectually stiffen and reinforce it, enabling the blade and the braces to withstand the strains exerted upon them in shoveling, particularly at the junction of the diagonal and straight portions of the braces, the wide or 70 double base-flanges of the T-irons contributing toward this desirable result.

The parallel upper portions of the braces are spaced to snugly admit the lower portion of the handle 10 between their web-portions 75 8, and allow the flat front side of the handle to bear against the inner flanges of the T-irons, as best shown in Fig. 3. The handle may be secured in place by any suitable means. The preferred devices shown in the 80 drawings consist of a pair of spaced staples or U-shaped bolts 11 which embrace the back and sides of the handle and the webs of the braces and pass forwardly through openings in the outer flanges of the braces, the blade 85 and yokes or washers 12 bearing against the face of the blade, these parts being tightly clamped together by the nuts 13 of the bolts which bear against said washers. By this construction, the blade is not only greatly 90 stiffened by the T-braces, but its separation from the braces by the stripping of the rivets 7 is prevented, inasmuch as the shoveling strain is exerted against the strong and stiff inner flanges of the braces, instead of 95 directly against the relatively thin and weak blade, as heretofore. While affording these advantages, the improvement does not materially increase the cost of the shovel.

I claim as my invention:

1. A shovel, comprising a blade, upwardly-converging T-iron braces secured to the back of the blade and having their base-flanges arranged against the blade, said braces having substantially parallel extensions at their upper ends, a handle arranged between said extensions and bearing against the inner base-flanges thereof, and means for securing the handle between said extensions.

2. A shovel, comprising a blade, upwardly-converging T-iron braces secured to

the back of the blade and having their base-flanges arranged against the blade, said braces having substantially parallel extensions at their upper ends, a handle arranged between the webs of said extensions and bearing against the inner base flanges thereof, a U-shaped bolt embracing the back and

sides of the handle and the webs of said brace-extensions, said bolts passing through the outer base-flanges of the extensions and 10 the blade, and a washer interposed between the blade and the nuts of said bolt.

CHARLES J. VOLKSTADT.
